UNITED STATES PATENT OFFICE.

ALBERT J. KRANTZ, OF STRASBURG, OHIO.

TARGET.

Application filed July 8, 1926. Serial No. 121,238.

This invention aims to provide a novel means for mounting a plurality of targets so that they may be tilted over into a prone position by the impact of a shot, novel means being provided for re-setting the targets.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Figure 1 shows in top plan, a device constructed in accordance with the invention;

Figure 2 is a side elevation;

Figure 3 is a side elevation wherein parts are in section, one of the targets having been knocked over by a shot;

Figure 4 is an end elevation;

Figure 5 is a cross section on the line 5—5 of Figure 2;

Figure 6 is a cross section on the line 6—6 of Figure 3;

Figure 7 is a cross section on the line 7—7 of Figure 2;

Figure 8 is a sectional view on the line 8—8 of Figure 2, remote parts being omitted;

Figure 9 is a section similar to Figure 8 but showing the operation of the adjusting means.

In carrying out the invention there is provided a support 1, which may be in the form of an elongated plate. A target 2 is fixed to the forward end of the support 1. The target 2 has an opening 3. Behind the target 2 are located any desired number of other targets, 4, 5, 6, and 7. The targets 4, 5 and 6 have openings 8, as shown in Figure 4 and as indicated in dotted line in Figure 2. The openings 8 in the targets 4, 5 and 6 decrease in diameter toward the rear end of the support 1, the said openings being in alinement with each other and in alinement with the opening 3 in the fixed target 2, the opening 3 being the largest of the openings.

The target 7 is imperforate as shown in Figure 7.

Each of the targets 7, 6, 5 and 4 has a forwardly extended foot 9 which forms a counter-weight. The targets 7, 6, 5 and 4 are equipped with lateral pivot elements 10 engaged in ears 11 on the sides of the support 1. Adjusting devices such as screws 12 are threaded into the support 1, and the foot or counterweight 9 of each target rests upon the corresponding screw 12. The screws 12 may be threaded in and out a little, in the support 1, as a comparison of Figures 8 and 9 will show, in order to cause each of the targets 7, 6, 5 and 4 to stand in a truly vertical position. The weights or feet 9 are so located with respect to the pivot means 10 for the various targets, as to hold the targets upright, as disclosed in Figure 2, prior to the impact of a shot, and the weights are so located with respect to the pivot elements 10 that, after any one target has been knocked down by a shot, as shown in connection with the target 5 in Figure 3, the target will lie prone until it is reset to vertical position. Each foot or weight 9 may carry on its bottom a number or other character, as shown at 14 in Figure 6, and when one or more of the targets are knocked over by a shot, the characters as shown at 14 may be used to make up a score. A glance at Figure 4 shows that the device presents practically the same appearance as an ordinary ring target marked on a single piece of paper, and the same degree of skill is necessary in connection with the target forming the subject matter of this application as is called in the use with any other target.

A resetting means of the various targets are provided. The resetting means includes 95 a yoke 15 provided at its ends with rotatable sheaves 16 over which are looped flexible elements 17, the ends of each flexible element 17 being joined to ears 18 on the weights or feet 9 of adjoining targets. To the intermediate portion of the yoke 15 is connected a forwardly extended jerk line 19. By pulling on the line 19, any or all of the targets which may have been knocked over by a shot, will be swung up into a vertical position. The flexible elements 17 slide in openings 20 in the fixed target 2. Owing to the fact that the flexible elements 17 are looped over the sheaves 16, the flexible elements will adjust themselves lengthwise, and there will 110 always be a fair pull on all of the targets, to aid in the resetting of them. The various

targets preferably are made of metal and will last a long time. The imperforate target 7 serves as a back stop for any projectiles which may pass through the openings 8 of all of the targets. The device may be used within a building, if desired, because there will be no lead spatter to speak of.

What is claimed is:—

1. In a device of the class described, a support, a target, pivot means connecting the target with a support, the target having a weight so located with respect to the pivot means as to hold the target upright prior to the impact of a shot and to permit the target 10 to lie prone after the impact of a shot, and an adjustable element cooperating with the weight and with the support to tilt the target, for adjustment, on the pivot means, thereby to adjust the position of the target 15 with respect to the vertical.
2. In a device of the class described, a support, targets tiltably mounted on the sup- 20

port and located one behind the other, a yoke, a flexible element looped slidably on the yoke, and means for connecting the ends 25 of the flexible element with the targets.

3. In a device of the class described, a support, targets located one behind the other and provided with cooperating openings of different sizes, pivot means connecting the 30 targets with the support, a weight carried by each target and so located with respect to the pivot means as to hold the target upright prior to the impact of a shot, the targets being spaced apart far enough so that 35 each target may lie prone after the impact of a shot, there being a characteristic scoring mark on the under side of each weight and exposed when the target lies prone, and means for resetting the targets from a re- 40 mote point.

In testimony that I claim the foregoing as my own, I have hereto affixed my signature.

ALBERT J. KRANTZ.
